THE NORRIS PETERS CO., PHOTO-LITHO., WASHINGTON, D.C.

UNITED STATES PATENT OFFICE.

THOMAS GREEN, OF WABASH, INDIANA.

DOOR FOR DRY-KILNS.

SPECIFICATION forming part of Letters Patent No. 657,532, dated September 11, 1900.

Application filed March 16, 1900. Serial No. 8,929. (No model.)

To all whom it may concern:

Be it known that I, THOMAS GREEN, a citizen of the United States, residing at Wabash, in the county of Wabash and State of Indiana, 5 have invented certain new and useful Improvements in Doors for Dry-Kilns, of which the following is a specification.

My invention relates to doors for dry-kilns, the object being to provide a door of light 10 durable construction which may be manufactured at small cost and operated as a hoisting-door with little labor and which will prevent the escape or radiation of heat.

The construction of the invention will be 15 fully described hereinafter in connection with the accompanying drawings, which form a part of this specification, and its novel features will be defined in the appended claims.

In the drawings, Figure 1 is a front elevation 20 of a door embodying the invention. Fig. 2 is a vertical section on the line 2 2 of Fig. 1. Fig. 3 is a transverse section on the line 3 3 of Fig. 1. Fig. 4 is a transverse section on the line 4 4 of Fig. 1, and Fig. 5 is a section 25 on the line 5 5 of Fig. 1.

The rectangular frame of the door comprises vertical bars 1, connected at top and bottom by transverse bars 2 and 3, which are each formed on their inner sides with equi- 30 distant recesses 4, within which are secured the ends of parallel vertical strips 5, constituting the outer side of the door. The bars 1 are connected on the outer side of the door by parallel cross-bars 6, mortised into the 35 side bars 1 and resting against the outer surface of the strips 5.

The inner side of the door comprises a series of parallel vertical strips 7, which are arranged to break joints with the outer strips 40 5. These strips 7 are secured together and to the cross-bars 2 and 3 by parallel trans- 45 verse bars 8, which are formed with equi- distant recesses 9, within which the strips 7 fit and are aligned horizontally with the outer cross-bar 6. Between the two sets of vertical overlapping strips 5 and 7 is interposed a sheet 10 of asbestos, which is firmly clamped between the front and rear strips.

11 designates a central longitudinal bar on 50 the outer side of the door, secured at its lower

end to the lower cross-bar 2 and extending through a slot formed in a horizontal flange 12, projecting from the upper cross-bar 3 of the door-frame. The projecting upper end 13 of the bar 11 is slotted to receive a wedge- 55 key 14, which secures the bar firmly to the door. The rear side of the bar 11 is formed with a series of recesses 15, through which the cross-bars 6 extend, and the outer side of the bar 11 is provided with an oppositely-in- 60 clined reinforcing projection 16, slotted at the points 17 and 18 for the sake of lightness in construction. The bar 11 is braced to the upper cross-bar 3 by oppositely-disposed inclined braces 19 and 20, the lower ends of 65 which are recessed to overlap each other and extend through the upper slot 17 of the bar 11, while their upper ends are recessed to fit the upper cross-bar 3.

Any suitable means for raising and lowering 70 the gate may be provided, the hoisting means not forming a part of the present invention.

As thus constructed the parts of the door are firmly secured together, and the sheet of 75 asbestos is firmly clamped between the outer and inner vertical strips. The asbestos confines the heat and prevents its escape by radiation, and thus materially contributes to the effectiveness of the kiln. 80

I claim—

1. A door for kilns, comprising a frame consisting of vertical and transverse bars; a series of parallel vertical strips on the outer side of the door; transverse bars secured to 85 said strips; a series of parallel vertical strips on the inner side of the door alternating with the outer strips and breaking joints therewith; and a sheet of asbestos interposed between the outer and inner strips, and clamped 90 in place thereby.

2. A door for kilns comprising a rectangular frame; a series of outer vertical strips; a series of inner strips overlapping and alternating with said outer strips; a sheet of asbestos clamped between the two series of strips; transverse securing-bars for the outer strips, and a central longitudinal bar secured to the outer strips of the door. 95

3. In a door for kilns; the combination with 100

a rectangular frame, of a series of outer vertical strips; a series of inner vertical strips; a sheet of asbestos between the two series of strips; and cross-bars for bracing and securing the strips, said cross-bars being formed with equidistant recesses to receive said vertical strips.

In testimony whereof I affix my signature in presence of two witnesses.

THOMAS GREEN.
